(57) **CLAIM**

The ornamental design for a wireless module, substantially as shown and described.

DESCRIPTION

FIG. 1 is front elevational view of a wireless module, showing my new design.

FIG. 2 is a rear elevational view thereof.

FIG. 3 is a top plan view thereof.

FIG. 4 is a bottom plan view thereof.

FIG. 5 is a left side elevational view thereof.

FIG. 6 is a right side elevational view thereof.

FIG. 7 is an isometric view thereof.

FIG. 8 is a front elevational view of a wireless module showing another embodiment of my new design.

FIG. 9 is a rear elevational view thereof.

FIG. 10 is a top plan view thereof.

FIG. 11 is a bottom plan view thereof.

FIG. 12 is a left side elevational view thereof.

FIG. 13 is a right side elevational view thereof; and,

FIG. 14 is an isometric view thereof.

Shading lines shown in the drawings are intended to represent the approximate three-dimensional contour of the design, and are not intended to indicate surface decoration. The broken lines are directed to environment and are for illustrative purposes only; the broken lines form no part of the claimed design.
